UNITED STATES PATENT OFFICE.

JOSEPH McLAUGHLIN, OF ELMIRA, OHIO.

CASKET-CARRIER.

SPECIFICATION forming part of Letters Patent No. 508,179, dated November 7, 1893.

Application filed May 8, 1893. Serial No. 473,470. (No model.)

To all whom it may concern:

Be it known that I, JOSEPH McLAUGHLIN, a citizen of the United States, residing at Elmira, in the county of Fulton and State of Ohio, have invented a new and useful Casket-Carrier, of which the following is a specification.

The invention relates to improvements in casket carriers.

10 The object of the present invention is to provide a simple, inexpensive and efficient casket carrier, adapted to be readily handled, and capable of conveniently conveying a casket in a church or house along narrow aisles 15 and passageways, where there is insufficient room to permit persons at both sides of the casket for the purpose of carrying the same.

The invention consists in the construction and novel combination and arrangement of 20 parts hereinafter fully described, illustrated in the accompanying drawings, and pointed out in the claims hereto appended.

In the drawings, Figure 1 is a perspective view of a casket carrier, the platform being 25 detached to show the running gear thereof. Fig. 2 is a reverse plan view.

Like numerals of reference indicate corresponding parts in all the figures of the drawings.

30 1 and 2 designate front and rear axles having journaled on their spindles wheels 3, which are provided with pneumatic tires; and the axles are secured by clips 4 to the centers or adjacent thereto to longitudinally disposed 35 side springs 5 5^a arranged in pairs at each axle. The rear side springs have their front ends secured to a transverse spring bar 6, and their rear ends are attached to the ends of a transverse spring 7, which is centrally secured by a clip 8 to a metallic spring casing 9. The spring casing 9 consists of triangular sides provided at their upper edges with securing flanges, and an oppositely inclined bottom on the apex of which is arranged the 45 clip 8.

The front axle has the rear ends of its side springs attached to the ends of a transverse spring 10, which is centrally secured by a clip 11 to the rear end of a V-shaped frame 12.

50 The V-shaped frame 12 has secured to it a

fifth-wheel consisting of a circular plate 13 secured to a bolster 14 and the lower circular plate 15, which is provided with flanges 16, and the latter are bent upward over the upper face of the upper plate 13, which projects 55 beyond a central circular portion 17. The plates of the fifth wheel are connected by a pivot 18, on which the front truck is free to turn completely to enable the casket carrier to make an exceedingly short turn.

60 The front ends of the sides of the V-shaped frame 12 are provided with flanges 19, provided with perforations, and adapted to be engaged by outwardly turned ends 20 of resilient diverging arms 21 of a handle 22, detachably connected with the front truck. The handle is preferably constructed of a single piece of rod iron, but it may be differently constructed.

70 The front and rear trucks support a platform 23, and it will be readily apparent that the casket carrier will enable a casket to be safely, conveniently and expeditiously conveyed through narrow passageways and aisles where there is insufficient space to permit persons to walk at each side of a coffin, and thereby avoids the dangerous and troublesome means usually employed for conveying a casket through such spaces, by causing it to be carried by two persons stationed at the 75 head and foot of it.

Changes in the form, proportion and the minor details of construction may be resorted to without departing from the principle or sacrificing any of the advantages of this invention.

80 The clips 4 which secure the side springs 5 and 5^a to the front and rear axles extend under the axles along the springs and are provided at their ends with pairs of lugs, which 85 are bent over upon the upper faces of the springs.

What I claim is—

1. A casket carrier comprising a platform, a spring bar secured to the lower face of the 95 platform, a spring casing constructed of metal and secured to the platform and consisting of triangular sides provided with securing flanges and an oppositely inclined bottom provided at its apex with a clip, a transverse 100

spring centrally secured to the casing by said clips, side springs attached to the spring bar and to the ends of the transverse spring, a rear axle clipped to the side springs, wheels 5 journaled on the axle, and a pivoted front truck having side and transverse springs, substantially as described.

2. In a casket carrier, the combination of a platform, a fifth-wheel, a V-shaped frame 10 secured to the fifth-wheel and provided at its front end with perforated flanges, a transverse spring centrally secured to the rear end of the V-shaped frame, side springs extend-

ing from the ends of the transverse spring to the front ends of the V-shaped frame, an axle 15 secured to the side springs, and a handle having diverging resilient arms provided with outwardly bent ends engaging the perforated flanges, substantially as described.

In testimony that I claim the foregoing as 20 my own I have hereto affixed my signature in the presence of two witnesses.

JOSEPH McLAUGHLIN.
